UNITED STATES PATENT OFFICE

2,511,757

CROWN SEALING DEVICE

Joseph Waldman, Irvington, N. J.

Application March 10, 1947, Serial No. 733,452

1 Claim. (Cl. 58—90)

1

The purpose of my invention is to provide an efficient means for sealing the winding stem aperture of a watch case by means of a valve-like arrangement between the watch case and the watch crown to thereby eliminate the likelihood of extraneous matter entering the watch case through said aperture.

The accompanying drawing illustrates embodiments of structures employing my invention described in detail in the ensuing specification. These embodiments are merely by way of example and the invention is not limited thereto but includes all other forms which would come within the scope or purview of the appended claim.

In the drawing:

Fig. 1 is a sectional, segmental view of the outer casing of a watch case of circular outline, embodying the invention.

Fig. 2 is a vertical, elevational, sectional view of a crown member used in carrying out my invention.

Fig. 3 is a vertical, elevational view of a spring member.

Fig. 4 is a vertical, sectional view of a cone-shaped shell member adapted to be used in connection with the crown member of Fig. 2.

Fig. 5 is a vertical, sectional view of the parts in position for assembling.

Fig. 6 is a view similar to Fig. 5 but showing the parts assembled, with the lower edge of the neck portion of the crown member inturned to preclude accidental displacement of the parts.

Fig. 7 is a view similar to Fig. 5, showing the parts assembled on a watch case with the crown threaded on the winding stem of a watch, shown fragmentarily, and

Fig. 8 is a view similar to Fig. 6, showing the application of the invention to a watch case of non-circular outline.

My invention is designed to provide a valve-like sealing arrangement between the watch case and watch crown, whereby the winding stem aperture of the watch case will be effectively sealed. Said aperture in the conventional watch case is a cylindrical opening defined by a straight wall. In accordance with the instant invention, the wall defining said opening is provided with a beveled portion somewhat along the general lines of a valve seat, and the watch crown is provided with a relatively thin walled annular member of a shape corresponding to a frustum of a cone, which member is slidably mounted on a depending portion of the crown and is maintained under tension against the conical por-

tion of the wall defining said opening to provide a seal, along the lines of a valve sealing arrangement.

As shown in the drawings, the watch crown 10 of my invention is provided with a circular rim portion 11, having a flange portion 12 and a depending neck portion 13, said neck portion 13 with the flange 12 defining an annular recess 14 for the reception of a spring 15 and a conical shell member 16, which shell member comprises a relatively thin walled annulus of a shape corresponding to a frustum of a cone. The outer casing 17 of the conventional watch case (in Fig. 1 said casing is shown as being of generally circular outline) is provided with a winding stem aperture 18 which is defined by a wall of generally circular outline. In accordance with my invention, the wall defining said aperture 18 is provided with a beveled portion 19 which, in effect, constitutes a valve seat on which the conical shell member 16 is urged in the manner of a valve seated on its valve seat. The spring 15 and conical shell member 16 are assembled in the annular recess 14 of the crown 10, and then the outer edge 20 of the flange 12 is inturned to project into the plane of the annular recess 14, precluding excessive movement or displacement of the spring and casing sealing member 16 outwardly of the annular recess 14.

As above stated, the shell member 16 comprises a relatively thin walled annulus which is frustoconical in shape, which member, when assembled in the annular recess 14 of crown 10, has its edge of greatest diameter slidably engaging the outer wall of recess 14 and its edge of smallest diameter slidably engaging the wall of the depending neck portion, which shell member is retained within said recess by engagement of its edge of greatest diameter with the inturned edge 20 of flange 12.

The assembled parts are shown in Figs. 6 and 7, in which last-mentioned figure the crown 10 is shown secured to the winding stem 21 of the watch, this being the normal position of the parts when the watch is in use. In Fig. 8 I have shown the application of the invention to a watch casing 17a of non-circular outline.

While I have shown in the drawings and have described in the above specification, a convenient form of structure embodying my invention, it will be apparent from such disclosure that the invention is capable of many modifications without departing from the spirit and scope thereof, as set forth in the appended claim.

Having thus described my invention, what I

claim as new and desire to secure by Letters Patent, is:

A crown for use with a watch case having a winding stem opening defined by a substantially cylindrical wall at least the outermost surface of which is inwardly and downwardly inclined, said crown including an outer depending flange, and a centrally-positioned depending neck portion adapted to be connected to the winding stem of the watch, the outer wall of said neck portion and the inner wall of said flange being circumferentially spaced to provide an annular recess therebetween, a shell comprising a relatively thin walled annulus which is frusto-conical in shape and which is slidable within said recess, 15 said shell having its edge of greatest diameter uppermost and in sliding contact with the inner wall of said flange and its edge of smallest diameter downward and in sliding contact with the outer wall of said depending neck portion, and 20 a spring within said recess and engaging said shell to move the same downwardly of said recess and into engagement with the opening in

said watch case when said crown is in position on the winding stem of the watch, the lowermost edge of said outer depending flange being bent inwardly after the spring and shell are placed in said recess, to underlie the edge of the shell of greatest diameter to limit outward movement of said spring and shell with respect to said recess.
